Primary Examiner — Michael A. Pratt(74) *Attorney, Agent, or Firm* — John A. Chionchio, Esq.; Ballard Spahr LLP(57) **CLAIM**

I claim the ornamental design for a pistol, as shown and described.

DESCRIPTION

FIG. 1 is a right side view of an embodiment of a pistol according to the invention;

FIG. 2 is a left side view of the pistol shown in FIG. 1;

FIG. 3 is a front view of the pistol shown in FIG. 1;

FIG. 4 is a back view of the pistol shown in FIG. 1;

FIG. 5 is a top view of the pistol shown in FIG. 1; and,

FIG. 6 is a bottom view of the pistol shown in FIG. 1.

The dotted lines in the figures form no part of the claimed design.
